SHOE FORM

James F. Clark and Edward B. Clark,
Toronto, Ontario, Canada

Application November 14, 1934, Serial No. 753,011

9 Claims. (Cl. 12—128.1)

This invention relates to a shoe form or tree for insertion into a shoe or other footwear to maintain the upper in a smooth distended condition for display or other purposes. The invention will best be understood by reference to the following description when taken in connection with the accompanying drawings of certain specific embodiments thereof, while its scope will be pointed out more particularly in the appended claims.

In the drawings:

Fig. 1 is a side elevation of a shoe tree exemplifying one form of the invention;

Fig. 2 is a bottom plan of the same;

Fig. 3 is a side elevation of the shoe tree shown in Figs. 1 and 2 as it appears before the outer covering is applied;

Fig. 4 is a central longitudinal sectional view of the shoe tree shown in Figs. 1 and 2;

Fig. 5 is a transverse sectional view on line 5—5 of Fig. 4;

Fig. 6 is a bottom plan of the shoe tree showing a modification of the means for holding the tree covering snugly in place;

Fig. 7 is a bottom plan of the shoe tree showing a second modification of the means for holding the covering in place;

Fig. 8 is a longitudinal sectional view of a modification in which there is provided a member secured to the rear upper portion of the body of the shoe tree and extending rearwardly therefrom; and

Fig. 9 is an elevation partly in section of a full length shoe tree embodying certain features of the invention.

Referring to the drawings and to the embodiments of the invention illustrated therein by way of example, and having reference at first to Figs. 1 to 5 inclusive, there is shown a shoe tree comprising a body 10 which has the general form of the interior of the forepart and a portion of the instep in a shoe, said body in this example being open at the bottom and rear. The body may be made of wood, light metal such as aluminum, cast or stamped, or of pressed or molded material such as fiber or various resinous materials, synthetic and otherwise. One suitable resinous material is a comparatively recent product known as "tenite".

The body is provided with a recess 12 about at least a portion thereof where it is adjacent the shoe upper, and in this example this recess occupies the toe and vamp portion. Within this recess is a resilient cushion 14, herein sponge rubber, which is well adapted to the purpose because

it is capable of yielding locally when subjected to local pressure without being distorted or expanded at other points. The outer surface of the cushion is continuous or flush with the outer surface of the body so as to present a smooth contour. In this example the cushion 14 is supplemented by another cushion 16, also of sponge rubber, on at least a portion, and herein along the marginal portion of the bottom of the body, as well as along the lower edge of the cushion 14. Thus, when the tree is placed in a shoe, both cushions are held under compression and cooperate to hold the upper of the shoe in smoothly distended condition. While the cushion 16 in the present example is shown separate from the cushion 14, a construction which can be manufactured very conveniently, they need not necessarily be formed separately, and the portion 16 of the cushion need not necessarily extend beneath the margin of the body 10 so long as it extends below the bottom of the latter.

In each of the forms shown in Figs. 1 to 8 inclusive, there is applied to the entire shoe tree a covering 18 of appropriate flexible sheet material, herein an elastic textile material, conveniently a portion of a stocking or sock. This is suitably cut and sewed together at the rear of the tree in any appropriate fashion to present a smooth neat appearance, and it is stretched on the inside of the body 10 so as to conform as closely as possible to the internal shape of the latter. However, to insure a snug fit, in the example shown in Figs. 2, 4 and 5, there is provided a strip 20 of appropriate flexible and herein resilient material such as celluloid anchored at its ends as by screws 22, the arrangement being such that the intermediate portion of this strip draws the central portion of the stocking material snugly against the body 10. Another way of accomplishing this result is by the use of one or more, herein several long strands of thread 24 (see Fig. 6) anchored at their ends in the stocking material as by sewing through the latter and stretching the strands tightly to cause the stocking material to be held snugly against the body. Another convenient means for this purpose is illustrated in Fig. 7 and comprises a strip 26 of elastic webbing having longitudinal strands 28 of rubber, and this strip is suitably secured in place as by screws 30 extending into the body.

The form shown in Fig. 8 is similar in all respects except that it is comparatively short, and for that reason the body is not recessed to receive the outer portion of the cushion. In this form, however, there is a member 32, herein in the na-

ture of a spring conveniently formed of appropriate material such as a wire or a strip which extends between the cushion 14 and the body 10 and is conveniently secured to the latter as by being bent downwardly at 34 and inserted into a hole 36 in the body. This strip extends from its point of attachment rearwardly, thence upwardly as at 38, and thence rearwardly, where it conforms generally to the curvature of the instep portion 10 of the shoe upper to form a support for the latter, and in the present example it extends rearwardly and downwardly as at 40 for engagement with the internal surface of the heel portion of the shoe, thereby to exert a forward pressure tending to keep the tree snugly in place in the forepart of the shoe. In other respects this form of the invention may be, and in the present example is like that which is illustrated in Figs. 1 to 5 inclusive, except that it is not recessed to receive the 20 cushion, but instead the latter extends to the rear end of the body.

In Fig. 9 there is shown a shoe tree which is full-length and comprises a body 42 provided with a recess 44 which, as shown, extends entirely about 25 the body to receive a cushion 46 of sponge rubber, and in this case also there is shown a supplemental cushion 48 of the same material applied to the lower edge of the main cushion and to the marginal portion of the body. It should be understood 30 that in all cases the cushion or cushions are suitably secured in place on the body as by cement. While the body 42 might of course be made of wood, either hollow or solid, and in the present case it is shown hollow, this body may be made 35 of molded or cast material, such, for example, as aluminum.

Having thus described certain embodiments of the invention, but without limiting ourselves thereto, what we claim and desire by Letters Patent to secure is:

1. In a shoe form for insertion into a shoe or other similar footwear, the combination of a member having the general form of the forward portion of the interior of a shoe, said member being 45 provided with a recess extending forwardly from a position approximately corresponding to a shoe vamp throat line toward the toe, and a sponge rubber-cushion within said recess and conforming to the shape of the flexible portion of a shoe upper 50 forward from approximately its vamp throat line, and said member having a substantially non-compressible section for supporting flexible portions of the shoe beyond its vamp throat line.

2. In a shoe form for insertion into a shoe or 55 other similar footwear, the combination of a body having the general form of the forepart of the interior of the shoe, said body being hollow and open at the bottom and rear, a sponge rubber pad disposed about at least a portion of said body to 60 contact with the interior of and to conform to the shape of the shoe upper, a covering of flexible material about said body and said pad and extending into said bottom and rear, and means extending lengthwise of and within said body on the outer surface of said covering to take up slack in 65 said covering.

3. In a shoe form for insertion into a shoe or other similar footwear, the combination of a body 70 having the general form of the forepart of the interior of the shoe, said body being hollow and open at the bottom and rear, a sponge rubber pad disposed about at least a portion of said body to 75 contact with the interior of and to conform to the shape of the shoe upper, a covering of flexible

material about said body and said pad and extending into said bottom and rear, and a flexible member extending lengthwise of and within said body on the outer surface of said covering, said member being anchored adjacent its ends and being under stress to urge said covering toward said body. 5

4. In a shoe form for insertion into a shoe or other similar footwear, the combination of a body having the general form of the forepart of the 10 interior of the shoe, said body being hollow and open at the bottom and rear, a sponge rubber pad disposed about at least a portion of said body to contact with the interior of and to conform to the shape of the shoe upper, a covering of flexible 15 material about said body and said pad and extending into said bottom and rear, and a resilient member extending lengthwise of and within said body on the outer surface of said covering, said member being anchored adjacent its ends and being tensioned to urge said covering toward said body. 20

5. In a shoe form for insertion into a shoe or other similar footwear, the combination of a body having the general form of the forepart of the 25 interior of the shoe, said body being hollow and open at the bottom and rear, a sponge rubber pad disposed about at least a portion of said body to contact with the interior of and to conform to the shape of the shoe upper, a covering of flexible 30 material about said body and said pad and extending into said bottom and rear, and a longitudinally elastic member extending lengthwise of and within said body on the outer surface of said covering, said member being anchored adjacent its ends and being under lengthwise tension to urge said covering toward said body. 35

6. A shoe tree comprising a core having an upper surface contour of the general shape of the fore-part of a shoe upper and having on such 40 surface a pad of cellular rubber extending forwardly from a position approximately corresponding to a shoe vamp line toward the toe, said pad having an upper surface contour conforming generally to the contour of the flexible fore-part of a shoe upper and being compressible over local areas by portions of a shoe upper forwardly of its vamp line and which do not conform with the pad surfaces without extruding the surface of other portions of the pad, and a substantially 50 non-compressible member conforming generally to the desired contour of flexible portions of a shoe upper beyond the vamp line of the shoe and adjacent to the portion supported by the rubber pad. 55

7. A shoe tree comprising a body of non-compressible material having a fore-part with an upper surface contour of the general shape of the fore-part of a shoe upper and a part projecting upwardly from said fore-part for the engagement of flexible portions of a shoe rearwardly of the vamp line thereof, said fore-part having thereon a pad of cellular rubber extending forwardly from a position approximately corresponding to a shoe vamp line toward the toe, said pad having an upper surface contour conforming generally to the contour of the flexible fore-part of a shoe upper and being compressible over local areas by portions of a shoe upper which do not conform with the pad surface without extruding the surface of other portions of the pad, and said angularly extending part having a substantially non-compressible surface and a contour conforming generally with the desired contour of flexible portions of the shoe upper. 70 75

8. A shoe tree comprising a hollow shell with a downwardly opening fore-part and a rearwardly opening part angularly disposed relative to said fore-part, said fore-part having the general form of the interior of the fore-part of a shoe in front of the vamp line and said angular part having the general form of the upper of a shoe behind the vamp line, and a pad on the surface of said fore-part and extending forwardly from a position approximately corresponding to a shoe vamp line toward the toe, said pad being composed of cellular material compressible over local areas by portions of a shoe upper which do not conform with the pad surface without extruding the surface of other portions of the pad.
9. A shoe tree comprising a hollow shell with a downwardly opening fore-part and a rearward-

ly opening part angularly disposed relative to said fore-part, said fore-part having the general form of the interior of the fore-part of a shoe in front of the vamp line and said angular part having the general form of the upper of a shoe behind the vamp line, and a pad on the surface of said fore-part and extending forwardly from a position approximately corresponding to a shoe vamp line toward the toe, said pad being composed of cellular material compressible over local areas by portions of a shoe upper which do not conform with the pad surface without extruding the surface of other portions of the pad, and a cushioning pad covering the lower edge of said fore-part of the shell.
